UNITED STATES PATENT OFFICE.

JOSEPH F. KELLER, OF NEW YORK, N. Y.

DESIGN FOR A TRACER AND CUTTER FRAME FOR DIE-SINKING MACHINES.

51,900.

Specification for Design.

Patented Mar. 26, 1918.

Application filed November 30, 1917. Serial No. 204,777. Term of patent 7 years.

To all whom it may concern:

Be it known that I, JOSEPH F. KELLER, a citizen of the United States, and a resident of New York, New York county, State of New York, have invented a new, original, and ornamental Design for Tracer and Cutter Frames for Die-Sinking Machines, of which the following is a specification, reference being had to the accompanying drawings, forming part thereof, in which—

Figure 1 represents a front view; Fig. 2 a top plan view; and Fig. 3 a rear view of the frame of my new design.

I claim:

The ornamental design for a tracer and cutter frame for die sinking machines, as shown.

In testimony whereof I have hereunto set my hand.

JOSEPH F. KELLER.
